(57) **CLAIM**

The ornamental design for a housing of a medical injector, as shown and described.

DESCRIPTION

FIG. 1 is a perspective view of the housing for a medical injector viewed from the front top;

FIG. 2 is a top plan view thereof;

FIG. 3 is a bottom plan view thereof;

FIG. 4 is a right side elevation view thereof;

FIG. 5 is a left side elevation view thereof;

FIG. 6 is a rear elevation view thereof;

FIG. 7 is a front elevation view thereof; and,

FIG. 8 is close-up of a partial portion of FIG. 2.

The broken line showing is for the purpose of illustrating portions of the article and forms no part of the claimed design. The broken line which defines the bounds of the claimed invention forms no part of the claimed design.

1 Claim, 4 Drawing Sheets
